UNITED STATES PATENT OFFICE.

ARTHUR VICTOR LEGGO, OF MELBOURNE, VICTORIA, AUSTRALIA.

ROASTING FURNACE.

Original application filed December 22, 1921, Serial No. 524,301. Divided and this application filed July 3, 1923. Serial No. 649,381.

To all whom it may concern:

Be it known that I, ARTHUR VICTOR Leggo, of 497 Collins Street, Melbourne, in the State of Victoria, Commonwealth of Australia, have invented certain new and useful Improvements in Roasting Furnaces, of which the following is a specification.

This invention relates to improvements in ore roasting furnaces and refers especially to certain improvements in the rabbling mechanism used in such furnaces. This application is a division of my prior application No. 524,301, filed December 22, 1921.

It is well known that the rabbling mechanism of a furnace being subject to great wear and tear requires more or less repair or replacement and attention to maintain its efficiency and as the furnace must be stopped during the time such repairs or replacements are being made, and as any break in the continuity of operations causes changes in temperature and in conditions which prejudice the efficiency of metallurgical operations, the more as the said changes are greater, it is of the utmost importance to reduce the time of making adjustments and repairs to a minimum.

The thorough exposure of the material under treatment to the furnace gases and even distribution of the same over the rabble paths, especially if large tonnages are handled, have hitherto presented difficulties which have only been minimized by means of costly and complicated arrangements of the rabbling mechanism. Moreover, the loss of capacity of a furnace during a prolonged stop for replacement of any part of the rabbling mechanism and during the period required after a long stop for the furnace to return to normal conditions militates to a great degree against economical working. The period required for replacement of broken or worn parts is often prolonged by the fact that under the extremely arduous conditions imposed by modern furnace practise the said parts become distorted and difficult to remove from the furnace when replacement becomes necessary, this being more pronounced as the complication of the rabbling mechanism is increased.

The present invention provides certain improvements in the rabbling mechanism of multiple hearth roasting furnaces to facilitate access to every part of the rabbling mechanism whereby renewals and repairs

therein can be effected in a minimum of time and whereby the disadvantages incidental to the cooling down of the furnace are minimized and whereby are effected greater efficiency, economy and flexibility than have been possible heretofore in roasting operations.

The improvements comprised in the present invention more particularly consist in the provision of simple and efficient means for detachably connecting the rabble arms to the rabble shafts whereby a water or air-tight joint is effected between the rabble arms and shafts so that the arms can be easily attached to and detached from the rabble shafts when working from the outside and from one side only of a furnace and in the provision of means for controlling the passage of a cooling medium through the rabble shafts and arms.

In order that the invention may be readily understood reference will now be had to the accompanying sheets of explanatory drawings wherein—

Figure 1 is a view in sectional elevation of part of a "straight line" multiple hearth furnace showing a rabble shaft with arms attached constructed in accordance with the present invention.

In this view the mechanism for effecting the rotation of the rabble shafts is shown located above the furnace.

Figure 2 is a view in sectional elevation of a rabble shaft and arms and shows means for introducing a cooling medium (more particularly water) thereto.

Fig. 2^a is a fragmentary side elevation, partly in section, showing the use of a fan in a modified form.

Figure 3 is a view in sectional plan of a rabble shaft and arm, and shows clearly the means for connecting the one to the other to form a water or air-tight joint. In this view a portion of the rabble arm is shown broken away for convenience of illustration.

Figure 4 is a view in sectional elevation of part of a rabble shaft and parts of rabble arms taken on the dotted line 4^a—4^a of Figure 3.

Figure 5 is a view in sectional plan of a rabble shaft and portion of a rabble arm showing a slight modification in the means employed for connecting the one to the other.

Figure 6 is a view in sectional elevation

taken on the dotted line 6^a—6^a of Figure 5.

Figure 7 is a view in perspective of part of the rabble shaft and the inner end of the rabble arm illustrated in Figure 3 showing clearly the construction of the same at the part to form a joint.

Figure 8 is a view in sectional plan of a solid rabble arm adapted to be connected to a rabble shaft by means of the joint shown in Figure 7.

Figure 9 is a view in sectional end elevation of the rabble arm shown in Figure 8 and taken on the dotted line 9^a—9^a.

Figure 10 is a view in end elevation of the rabble arm shown in Figure 8.

In these drawings the numeral 13 designates a rabble shaft which is supported at its lower end in a footstep bearing and is driven in any approved way.

20 The hollow rabble shaft passes through the centre of the furnace and has its lower end supported adjustably in a footstep bearing 23' located below the furnace. Portion only of a multiple hearth furnace is shown 25 in Figure 1 and is designated by the numeral 1.

If cooling is effected by circulation of air it is more convenient to place the driving gear below the lowest hearth and to withdraw 30 the heated air from the top of the rabble shafts by suction produced by any well known means.

The rabble shafts 13 are made hollow and cooled by water or air and at a point above 35 each hearth the rabble shafts are fitted with detachable rabble arms 36 which also are made hollow when a cooling medium is employed, and solid when the circulation of a cooling medium therethrough is not required.

40 The rabble arms are arranged alternately on opposite sides of the rabble shafts as shown in Figures 1 and 4 and at points above each hearth the sides of the shafts 45 are formed with outwardly flared sockets 37 into which fit correspondingly shaped spigots 38 formed on the inner ends of the rabble arms (see Figures 3 and 4).

The butt end of the rabble arm on both 50 sides of the spigot, is formed with jaws 39 which are adapted to engage and slide freely in recesses 40 formed horizontally in the sides of the rabble shaft (see Figures 2 and 7).

55 The recesses 40 in the sides of the rabble shaft are parallel to the axes of the sockets and are shaped to accommodate and form guides for the jaws 39 thereby enabling the spigots to be easily and correctly introduced into the sockets when working through observation holes in one or both sides of the furnace.

When the jaws 39 on the rabble arms are placed in engagement with the recesses 40 60 on the sides of the shafts, gibs 41 and

cotters 42 are inserted into slots 43 formed horizontally in the outer end of the said jaws.

The cotters and gibs are adapted to bear against the rabble shaft and the backs of the slots, respectively, and when the cotters are driven into place they will draw the tapered spigots tightly into the tapered sockets and thereby form a water or air-tight joint between the rabble arms and shaft.

The interfitting conical faces of the spigots and sockets are made to template so that when the former are introduced into the latter and drawn inwardly by tightening the cotters, the said conical faces will bear hard against each other and their nicety of fit ensures a perfectly water-tight joint.

85 The conical faces are the only parts of the joint which bear against each other and therefore the tighter the cotters are driven, the more the spigot is drawn into the socket and the greater is the pressure between the said faces.

In the modified form of the joint shown in Figures 5 and 6 of the drawings a spigot 44 is formed on the side of the shaft so as not to project beyond or only slightly beyond the circumference 95 thereof or any protective covering thereon and the entrance to the hollow rabble arm is flared to form a tapered socket 45 which is adapted to fit neatly over the said spigot on the shaft. The joint shown 100 in Figures 5 and 6 provides a maximum amount of opening from the shaft to the arm and consequently ensures ample freedom for the circulation of cooling medium from one to the other. Moreover this form 105 of joint is such that the shaft is not unduly weakened at the point of greatest load by having in it a large opening for the attachment of the arm, thus enabling a smaller and cheaper shaft to do the work efficiently. 110

Apart from those constructional details consequent upon reversal of the socket and spigot the joint is constructed as shown in and described with relation to Figures 3 and 4 of the drawings.

115 The passages through the hollow rabble shafts are somewhat restricted at the points 46 where the arms are connected thereto in order to compensate for the reduction of metal due to the formation of the guide recesses 40 and the sockets 37 and spigots 44 and to provide a sufficient body of metal at these points to ensure a requisite amount of strength.

120 The recesses 40 in the sides of the rabble shafts engage the jaws on the arms more or less neatly so as to ensure the arms being supported in or approximately in their normal horizontal positions without necessitating any other support, thereby enabling 125

the cotters and gibbs to be easily and quickly placed in position when assembling the parts.

A horizontal recess 48 (Figure 6) or shoulder 49 (Figure 4) is formed on the rabble shaft just above the axis of each joint and on the opposite side of the said shaft to that on which the said joint is located. When the cotters 42 are driven into position they are adapted to bear against the upper 10 walls of the recesses 48 or against the shoulders 49 thereby ensuring the rabble arms being maintained horizontally. If the position of the cotter is such that it does not bear against the top of the recess 48 or shoulder 49, the space above the said cotter is packed in any suitable manner thus ensuring that any arms not made quite accurately can still be used efficiently in the furnace.

The bearing between the cotter and the 20 top of the recess or shoulder relieves the joint of any stresses consequent upon the overhanging strain of the arm and the purpose of the packing is to ensure an effectual bearing between the said cotter and the upper end of the recess or the shoulder.

The alternate arms on each shaft may project from opposite sides thereof or they can be arranged to project from more than two sides of the shaft or in any other approved 30 way.

The hollow rabble arms and shafts can be formed without central partitions as shown in Figure 3 or they can be formed with partitions as shown clearly in Figures 2 and 5 35 of the drawings.

When the hollow rabble arms 36 are formed with central vertical partitions 50 the said partitions extend from the inner 40 ends near to the outer ends of the said arms and the inner ends of the said partitions are adapted to abut more or less neatly against central vertical partitions 51 in the rabble shafts when the arms are secured in position thereto.

In order to ensure a water tight or an 45 approximately water tight joint between the partition 50 in the rabble arm and the partition 51 in the shaft, a filling piece 52 of suitable material is interposed between the adjacent edges of the said partitions. This 50 filling piece will ensure a satisfactory joint when the spigot and socket connections will not permit of sufficient "take up" to allow of the said partitions abutting close enough 55 to effect a satisfactory circulation of a cooling medium through the shaft and arms.

The filling piece prevents the cooling medium "short circuiting" through the gap between the adjacent parts of the partitions 60 and ensures the said cooling medium being directed to the end of the rabble arm. The filling piece in no way assists in forming a water-tight joint between the arm and the shaft and even if it does not completely 65 fill the gap it will be more or less effectual

in directing the cooling medium into the arms.

The abutting edges of the partitions 50 and 51 can be made plain or they can be shaped as shown in Figure 5 of the drawings to 70 more effectually prevent the "short circuiting" of the cooling medium in its passage from the shaft to the arms.

The vertical partition 51 of the rabble shaft extends nearly the full length thereof 75 and the ends are turned in opposite directions at 53 and unite with opposite sides of the interior of the rabble shaft.

The partition in the rabble shaft divides the interior thereof into two separate vertical chambers 54 and 55 so that when a cooling medium is delivered from a supply pipe 56 to the upper end of the chamber 54, it will flow therefrom along one side of the partition 50 in a rabble arm and back the 80 other side of the said partition into the second chamber 55 in the rabble shaft and thence to an overflow 57 provided for the discharge thereof (see Figure 2).

The means hereinbefore described for connecting the arms to the shaft so as to make an effective joint therebetween is equally applicable in those cases where the shaft and arms are not provided with partitions for governing the circulation of a cooling 85 medium therethrough which may then be passed into the shaft through a pipe 57'. The pipe 57' depends within the shaft to a point below the bottom arm thereon and the cooling medium passes from the lower end of the said pipe and in ascending the shaft it circulates through the arms attached thereto (see Figures 3 and 4).

When the shaft and arms are cooled by 90 air the air is drawn from the upper end of the shaft by means of a fan or other draught inducing means of ordinary type and the air is drawn into the bottom of the shaft through holes 58 in the sides thereof.

A solid arm 36 is shown in Figs. 8 to 10 95 of the drawings, and this arm is attached to the rabble shaft 13, as above described, and is provided with a front flange 82 and a rear flange 83 constructed as shown in the other views, so that the rabble teeth can be attached thereto, as shown in Fig. 1 of the drawing.

The passage at the side of the partition 50 in the rabble arm through which the cooling medium is passed from the rabble shaft 110 can be provided at the entrance thereof with a transverse wall 50' (shown in dotted lines in Figures 5 and 6), having an opening 50" the size of which determines the amount of 115 cooling medium flowing from the shaft to the arm.

The difference in the sizes of the openings 50" result in a differential circulation 120 through the arms and the sizes of the said openings may therefore depend upon the lo- 125

cation of the arms within the furnace and the amount of cooling medium it is desired to pass to the particular arm or arms.

In some cases it is found advantageous to prevent a circulation of cooling medium through one or more of the arms on a shaft and to cause a differential circulation of the cooling medium through the remaining arms and this is accomplished by blocking the entrances 50" to the passages in the first mentioned arms and by providing openings of different sizes leading to the passages in the last mentioned arms.

The hereinbefore described improvements in the rabbling mechanism of ore roasting furnaces are applicable to "straight line" and in some instances to "turret" multiple hearth furnaces and by the substitution, removal or addition of certain parts hereinbefore described different kinds and conditions of work can be effectually performed and such arrangement of the parts as are most suitable to a particular requirement can be readily effected by any person skilled in the art.

I claim:

1. In roasting furnaces, a hollow rabble shaft having rabble arms detachably fitted thereto, partitions in the shaft and arms adapted to align with each other for governing the circulation of a cooling medium therethrough, means for supplying cooling medium to the shaft, means for effecting a differential circulation through the arms, tapered spigot and socket joints between the arms and shaft, slots in the arms, and tapered keys in the slots for drawing into and maintaining in contact the tapered faces of the spigots and sockets to effect a watertight joint between the shaft and arms.

2. In roasting furnaces, a hollow rabble shaft having a rabble arm fitted detachably thereto, a tapered spigot and socket joint between the arm and shaft, jaws on the inner end of the rabble arm adapted to engage the rabble shaft, and means for drawing into and maintaining in contact the tapered faces of the spigot and socket to effect

a watertight joint between the said shaft and arm.

3. In roasting furnaces a hollow rabble shaft having a rabble arm fitted detachably thereto, a tapered spigot and socket joint between the inner end of the arm and the shaft, recesses in the sides of the shaft, jaws on the inner ends of the arm adapted to slide in the recesses in the sides of the rabble shaft, and means for maintaining the tapered faces of the spigot and socket tightly in contact.

4. In roasting furnaces a hollow rabble shaft having a rabble arm fitted detachably thereto, recesses in the sides of the rabble shaft, jaws on the inner end of the arm adapted to slide in the recesses in the rabble shaft, slots in the outer ends of the jaws, a cotter and gib passing through the said slots, and a recess in the back of the rabble shaft against the upper end of which the cotter is adapted to bear.

5. In roasting furnaces a vertical hollow rabble shaft having an outwardly flared socket in the side wall thereof, a rabble arm having a tapered spigot on its inner end adapted to fit neatly in the flared socket, jaws on the inner end of the rabble arm on both sides of the spigot adapted to engage the rabble shaft, and a cotter for drawing the spigot tightly into the socket and for securely fastening the arm to the shaft.

6. In roasting furnaces, a hollow rabble shaft having a hole formed radially therein, a tapered spigot formed on the side wall of the shaft and surrounding the hole therein, a rabble arm having a tapered socket formed on the inner end thereof and adapted to fit neatly over the spigot, jaws on the inner end of the arm on both sides of the socket and adapted to engage the shaft, and a cotter for securely fastening the rabble arm on the shaft.

In testimony whereof he has affixed his signature.

ARTHUR VICTOR LEGGO.
